UNITED STATES PATENT OFFICE.

ANDREW L. WEST, OF KNOXVILLE, TENNESSEE.

SAFE AND VAULT DOOR.

Application filed November 3, 1921. Serial No. 512,475.

To all whom it may concern:

Be it known that I, ANDREW L. WEST, a citizen of the United States, residing at Knoxville, in the county of Knox and 5 State of Tennessee, have invented a new and useful Improvement in Safe and Vault Doors, of which the following is a specification, reference being had to the accompanying drawing.

10 My improvement relates particularly to auxiliary mechanism applied to the ordinary locking mechanism of safe and vault doors. The object of the improvement is to provide means whereby the bolt frame of a safe or 15 vault door is engaged and held immovably by auxiliary mechanism when the ordinary combination lock is disturbed by a burglar.

In the accompanying drawings,

20 Fig. 1 is an elevation of the inner face of a door embodying my improvement;

Fig. 2 is an upright section on the line, 2—2, of Fig. 1, looking toward the left;

Fig. 3 is an upright section on the line, 3—3, of Fig. 1, looking toward the left;

25 Fig. 4 is an upright section on the line, 4—4, of Fig. 3, looking toward the right.

Referring to said drawings, A is the body of the door. A¹ is the outer upright bolt rail fixed on the door in the usual manner. 30 A² is the inner upright bolt rail similarly applied to the door. A³ is the upper door rail. A⁴ is the lower door rail.

B, B are horizontal bolts, of usual form, 35 slideable in the bolt rails, A¹ and A², in the usual manner. B¹ is the usual bolt bar placed near and parallel to the bolt rail, A¹, and across the bolts, B, and secured rigidly to the latter, so that said bar and said bolts form a bolt frame which is slideable horizontally, the outer ends of the bolts engaging 40 in the door frame (not shown) when said frame is moved to its limit toward the outer bolt rail.

The combination lock, C, is located between the bolts, B, near the bolt bar, B¹, and 45 is of any ordinary construction and has any ordinary form of means for engaging the bolt bar or some part supported thereby to prevent the movement of said bar away from the outer bolt rail when the bolt frame has been moved to its limit toward the outer bolt rail.

In the upper face of one of the bolts, B, 50 is a notch, B², which is adjacent the inner face of the bolt rail, A², when the bolt frame

is at its limit toward the bolt rail, A¹. A key member, D, is located beside the inner bolt rail and has a throat which receives the bolt, B, and above said bolt said key member has a lip, D¹, which is adapted to enter said notch, B². Said throat is wide enough to permit up-and-down movement of the key member to bring said lip into or out of said notch. Retainers, D², applied to the inner face of the door and the adjacent face of the bolt rail, A², limit the key member to up-and-down movement. On the lower part of the key member is an eye, D³, to which is attached the upper end of a contracting coiled spring, D⁴. The other end of said spring is attached to an eye, D⁵, which is seated on the inner face of the door far enough below the key member to put said spring under sufficient strain to make it tend to draw the key member downward so as to make the lip, D¹, enter the notch, B², when the latter is moved beneath said lip.

55 A cord or chain or wire or similar tension member, E, has one end applied to an eye, D⁶, on the upper end of the key member. Said tension member leads from said eye upward and along the inner face of the door above the combination lock, C, and then downward between the combination lock and the bolt rail, A¹. Below the combination lock, the end of said tension member is attached to a screw post, E¹, seated on the inner face of the door. Between its ends, the tension member is led through guide members, E². One of said guide members is 60 locked near each upper corner of the combination lock, whereby the part of the tension member which is located above the combination lock is unsupported. By forcibly moving said part of the tension member upward along the face of the door, the part of the tension member which leads to the key member is drawn upward. By this action, the key member is drawn upward against the action of the coiled spring, D⁴. Such upward movement is limited by engagement of the lower wall of the throat of the key member against the lower face of the adjacent bolt. In such position, the lip, D¹, is 65 above the upper face of said bolt. Hence the bolt may move endwise in either direction without being hindered by the key member.

70 A yoke G, extends across the combination lock and toward the door below said lock almost to the inner face of the door. Thence 75

said yoke extends obliquely downward until its lower end bears against the inner face of the door. A post G^1 , seated on the door extends through the yoke and has its outer end threaded and on said end is a nut, G^2 . To the upper end of the yoke, G , is secured one end of a brace, G^3 , by means of a hinge, G^4 . Said brace and said yoke are so proportioned as to adapt the free end of the brace 10 to bear against the inner face of the door when said end is higher than said hinge and higher than the adjacent guides, E^2 . On the upper face of the brace and near its base, there is a shoulder or projection, G^5 , which 15 normally engages the tension member. The length of the tension member is made such as to permit said member to be engaged by the brace when the key member has been raised to its upper limit.

20 The force with which the yoke bears toward the door may be varied by adjusting the nut, G^2 , on the post, G^1 .

As above indicated, when the parts are in this position, the bolt frame can be repeatedly moved horizontally in either direction without hindrance by the key member, such movements of the bolt frame being effected by turning the ordinary knob or handle (not shown) associated with the bolt bar.

30 When a burglar, attempting to open the door, displaces the combination lock by hammer blows or by drilling, or by blasting, such displacement forces the upper end of the yoke, G , away from the inner face of 35 the door, whereby the brace, G^3 , is made to release the tension member, E . It is to be observed, also, that hammer blows on the outer face of the door adjacent the brace, G^3 , may cause the brace to release the tension member. Furthermore, any drilling or 40 burning or explosion which will lead to the severing or detaching of the tension member will cause the release of the key member, D , and allow it to be moved into engagement 45 with the adjacent bolt, B .

As soon as the tension member is thus freed, the contracting coil spring, D^4 , draws the key member, D , downward, whereby the lip, D^1 , is drawn into the notch, B^2 , in the 50 adjacent bolt, B . Here it is to be remembered that when the door is locked, said notch is in alignment with said lip.

Attention is invited to the fact that the inner bolt rail, A^2 , of the door forms a substantial abutment for the key member, D , the key member resting flatwise against the face of said rail and sliding up-and-down against said face. When the key member is engaged in the notch, B^2 , of the lock bolt, 60 all strain put upon this bolt to move it out of the locked position will be put upon the bolt rail, A^2 , because the key member, as above stated, rests against said rail. That is the major or dominating strain which is 65 to be considered, and it will be seen that the

bolt rail is amply strong to resist that strain. Tendency in the key member to move horizontally away from the bolt rail involves small strains, and said strains are easily resisted by the retainers, D^2 , which need not be of strong construction. To give the key member this strong seating, no work need be done on the door excepting the making of small holes for the small screws used for attaching the retainers. The yoke, G , is adjustably secured by only the screw post, G^1 , seated on the inner face of the door.

It is to be understood that the guide members for the tension member may be of such number and may be located in such places as may be deemed expedient. It is also to be understood that the yoke may vary in form to meet varied conditions.

I claim as my invention,

1. In an apparatus of the nature described, the combination with a door and a combination lock and a locking bolt having a notch, of a key member movable transversely to the length of said bolt and adapted to engage in said notch, constantly acting means tending to move said key member in the direction to make such engagement, a yoke and a brace yieldingly positioned adjacent the combination lock, and means extending from the brace to and into engagement with said key member for normally holding said member in position to avoid engagement with said bolt, said brace being adapted to be released by attempts to derange the locking mechanism, substantially as described.

2. In an apparatus of the nature described, the combination with a door and a combination lock and a locking bolt having a notch, of a key member movable transversely to the length of said bolt and adapted to engage in said notch, constantly acting means tending to move said key member in the direction to make such engagement, an adjustable yoke, and a brace yieldingly positioned, and means extending from the brace to and into engagement with said key member for normally holding said member in position to avoid engagement with said bolt, said brace being adapted to be released by attempts to derange the locking mechanism, substantially as described.

3. In an apparatus of the nature described, the combination with a door and a combination lock and a locking bolt having a notch, of guide members adjacent the combination lock, a key member movable transversely to the length of said bolt and adapted to engage in said notch, constantly acting means tending to move said key member in the direction to make such engagement, a tension member extending from said key member away from said notch in the direction opposed to said constantly-acting means and through said guide members, and

a displaceable member located adjacent the combination lock and engaging said tension member between two of said guide members and holding said tension member out of alignment with said guide members, whereby said key member is held out of engagement with said notch, substantially as described.

4. In an apparatus of the nature described, the combination with a door and a combination lock and a locking bolt having a notch, of guide members adjacent the combination lock, a key member movable transversely to the length of said bolt and adapted to engage in said notch, constantly acting means tending to move said key member in the direction to make such engagement, a tension member extending from said key member away from said notch in the direction opposed to said constantly acting means and through said guide members, and a displaceable member located adjacent the combination lock and having a shoulder engaging said tension member between two of said guide members and holding said tension member out of alignment with said guide members, whereby said key member

is held out of engagement with said notch, substantially as described.

5. In an apparatus of the nature described, the combination with a door and a combination lock and a locking bolt having a notch, of a key member movable transversely to the length of said bolt and adapted to engage in said notch, constantly acting means tending to move said key member in the direction to make such engagement, a yoke extending across the combination lock and having one end resting on the inner face of the door, adjustable means engaging said yoke between said end and the combination lock, a brace engaged by the other end of said yoke, and means extending from the brace to and into engagement with said key member for normally holding said member in position to avoid engagement with said bolt, said brace being adapted to be released by attempts to derange the locking mechanism, substantially as described.

In testimony whereof I have signed my name this 24th day of October, in the year one thousand nine hundred and twenty-one.

ANDREW L. WEST.
